PORTRABLE STRAPPING STAND

Edward T. Wayne, 67 Clinton St., Binghamton, N.Y.

Filed July 12, 1960, Ser. No. 61,314

Term of patent 14 years

(Cl. D14—3)

Fig. 1

FIG. 2

FIG. 1 is a perspective view of a portable strapping stand showing my new design;

FIG. 2 is a rear elevational view thereof.

The reel shown in broken lines is included for illustrative purposes only.

I claim:

The ornamental design for a portable strapping stand, as shown and described.
